US00D786199S

(12) **United States Design Patent** (10) Patent No.: **US D786,199 S**
(45) Date of Patent: ** May 9, 2017

(54) **COMPRESSOR CONTROL**

(71) Applicant: **KAESER KOMPRESSOREN SE**,
Coburg (DE)
(72) Inventor: **Michael Suthmann**, Kranzberg (DE)
(73) Assignee: **KAESER KOMPRESSOREN SE**,
Coburg (DE)
(**) Term: **15 Years**
(21) Appl. No.: **29/532,532**
(22) Filed: **Jul. 8, 2015**
